UNITED STATES PATENT OFFICE.

WILLIAM W. CONNER, OF SEWAREN, NEW JERSEY.

REFRIGERATING APPARATUS.

Application filed July 14, 1926. Serial No. 122,291.

This invention relates to refrigerating apparatus and more especially to that type of apparatus in which a gas such as ammonia is compressed, passed through a condenser where it is liquefied, conducted in liquid form to a receiver, allowed to expand in a refrigerating room or ice-making tank, and the cycle repeated.

In an apparatus of this type, the ammonia often becomes contaminated with permanent or non-condensable gases which accumulate in the system due to air being drawn in through pipe leaks or stuffing boxes on the low pressure portion of the system and the decomposition of lubricating oil in the compressor. It is also possible that under certain conditions the refrigerant itself may be decomposed to some extent, forming a permanent gas. When the refrigerant is thus contaminated, the efficiency of operation of the apparatus is decreased, and it is customary to vent the permanent gases. The escaping gases may and usually do contain an appreciable amount of ammonia vapor which, if allowed to escape from the system, would reduce the amount of refrigerant therein and would require continuous additions of fresh refrigerant.

An object of this invention is a simple, efficient and inexpensive purging apparatus for removing the contaminating gases from the system without loss of an appreciable amount of the refrigerant and which may be quickly and easily attached to a standard refrigerating system.

According to the invention, the apparatus comprises a purging chamber located above the receiver of the system and so connected thereto that vapor in the receiver may rise into the chamber and liquid in the chamber will drain by gravity into the receiver. In the chamber is provided a cooling or expansion coil through which a portion of the refrigerant is circulated to maintain the temperature in the chamber low enough to condense any ammonia gas carried into the chamber with the non-condensable gases. The purging chamber may also be connected to other parts of the system so that gases collected elsewhere than in the receiver may

be purged and the condensed ammonia refluxed to the receiver. From the purging apparatus, a vent pipe discharges the non-condensable gases into a water bottle which provides a visible indication of the vapor or gas being removed from the receiver.

This apparatus permits the purging operation to be carried on to completion without interruption. When the condition of the ammonia is such as to require purging, a valve controlling the connection between the receiver and the chamber is opened and a valve controlling the flow of refrigerant to the cooling coil is opened. The gas and vapor from the receiver flow through the purging chamber, the ammonia gas being condensed therein and draining back to the receiver through the same pipe through which the gases are led from the receiver to the chamber and the non-condensed gases passing out through the discharge to the water bottle. When the appearance of the bubbles in the water bottle indicate that all the non-condensed gases have been vented, the valves are shut off but up until this time no regulation is required. If it is desired to purge the refrigerant from another portion of the system, the gas and vapor therefrom are led to the purging chamber where the ammonia is condensed and drained into the receiver.

Other objects, novel features and advantages of the invention will be apparent from the following specification and accompanying drawings, wherein—

Figure 1 is a diagrammatic view of a part of a refrigerating system equipped with a purger embodying the invention; and

Fig. 2 is an enlarged detail of the purging chamber.

10 represents the receiver of a refrigerating system to which liquid ammonia under pressure is supplied through a pipe 11 from the condenser 12 to which ammonia in vapor form has been supplied through the pipe 13 from the usual compressor (not shown) of such a system. Liquid ammonia is supplied from the receiver 10 to the usual refrigerating room or ice-making tank (not shown) through a pipe 14, a T valve 15 and

a pipe 16 leading from one of the branches of the valve. In the operation of this apparatus, ammonia gas at relatively high pressure and temperature is supplied from the 5 compressor to the condenser 12 where it is reduced in temperature sufficiently to render it liquid, after which it is conducted into the receiver 10 by the pipe 11, the pressure still being maintained. From the receiver 10 the refrigerant is led to the refrigerating room or ice-making coils where it is allowed to expand, thereby cooling the room or coil. From the refrigerating room or coil, it is sucked into the compressor and the cycle 15 repeated. While circulating through the system, the ammonia becomes contaminated with certain fixed or non-condensable gases or air which increases the pressure in and decreases the efficiency of the system and 20 which, in the absence of any liquid traps in the system, collect in the top of the receiver 10.

A vent is provided for removing these 25 gases from the receiver. This vent comprises a chamber 17 supported above the top of the receiver 10. A pipe 18 leads from the bottom of the chamber 17 to a T fitting 19, to one arm of which is connected a pipe 20 through a valve 21, the pipe 20 being in 30 communication with the top of the receiver 10. A pipe 22 leads from the top of the chamber 17 and discharges into a water bottle 23, a valve 24 being provided in the pipe 22. Within the chamber 17 is arranged an 35 expansion or cooling coil 25, one end of which is connected through a valve 26 and pipe 27 with the suction side of the compressor of the system and the other end of which is connected through pipe 28, valve 29 and valve 30 with the remaining arm of the T valve 15. Within the coil 25 is arranged a series of baffles 31 by means of which the 40 escaping gases and vapors are directed into contact with the turns of the coil. A gauge 45 glass 32 is mounted on the chamber 17 so that the presence therein of liquid may be indicated. The chamber 17 is provided with a layer 33 of insulating material.

When it is desired to purge from the 50 system the contaminating gases collected in the upper part of the receiver 10, the valve 21 is opened, thereby permitting the contaminating gases and any vaporized ammonia contained therein to rise into the chamber 55 17. The valves 26, 29 and 30 are opened to permit the flow of refrigerant from the receiver 10 through the coil 25 and to the suction side of the compressor, the valve 29 being cracked and acting as an expansion 60 valve. The refrigerant in the coil 25 reduces the temperature in the purging chamber 17 sufficiently that any ammonia vapor carried off with the contaminating gases is condensed. The condensate refluxes through the 65 pipes 18 and 20 into the receiver 10 and ad-

ditional gas and vapor flow in. The valve 24 is cracked to permit the non-condensable gases to flow off through the pipe 22 into the water in the bottle 23. The discharge of vapor and gas from the receiver into the chamber and 70 the removal of the uncondensable gases from the chamber are kept up without interruption until all the non-condensable gases have been purged from the receiver. This condition will be apparent from observation of 75 the bubbles passing through the water bottle or by the indication in the gauge glass 32 of liquid in the chamber 17. The valves are then closed until further purging is required. 80

Connections are provided by means of which gases may be purged from other parts of the system. For example, a pipe 34 leads from the inlet to the condenser 12 through a valve 35 to the valve 36 which is connected to one arm of the T fitting 19. By opening the valves 35 and 36 and cracking the valve 24, gases accumulating in the condenser may be conducted to the chamber 17. At the same time, the valve 21 is cracked, thereby permitting ammonia condensed in the chamber 17 to drain into the receiver 10. The cracking of the valve 21 will permit liquid to drain into receiver 10 without permitting the flow of any appreciable amount of vapor or gas due to the fact that the condenser and receiver are subjected to the same pressure. It is apparent, of course, that connections may be made to other parts of the system, if desired, whereby gas may be vented therefrom through the purging chamber 17. 95

To supply the system with fresh refrigerant, there is provided a supply pipe 37 communicating with the pipe 28 through a valve 38. Also a sight glass 39 is attached to the receiver by means of which the level of the liquid refrigerant in the receiver 10 may be indicated. 100

With this apparatus, permanent gas collected in the system may be removed therefrom without any substantial loss of refrigerant. Any vaporized ammonia carried off with the non-condensable gases will be condensed in the chamber 17 and will return to the receiver by gravity. Because of the return of the condensed refrigerant directly to the top of the receiver, the purging operation may be carried on continuously until such time as the system has been freed of the non-condensable gases, which condition may be determined by observation of the sight glass 32 or the condition of the bubbles in the water bottle 23. Little or no attention to the apparatus is required during the purging operation, and it is not necessary to regulate the valves between the starting and completion of the operation. The condensed refrigerant is returned to the system, thereby preventing loss thereof and the refrigerant utilized in condensing the ammonia. 110 115 120 125 130

nia is also returned to the system after its expansion.

The above-described apparatus which is of simple structure and of small cost has proven highly efficient and has been used with great success in several large refrigerating installations. While a particular embodiment of the apparatus has been disclosed herein, it is to be understood that various structural changes may be made without departing in any way from the spirit of the invention as set forth in the appended claims.

Having thus described my invention, what I claim as new and desire to secure by Letters Patent of the United States is:

1. In a refrigerating system, a receiver, a purging chamber supported above said receiver, the top of said receiver and the bottom of said purging chamber being in communication through a passageway of materially smaller cross section than said purging chamber, a cooling coil in said chamber, a conduit for supplying refrigerant from said receiver to said coil, and a vent from said chamber for uncondensed gases.

2. In a refrigerating system, a receiver, a purging chamber supported above said receiver, a cooling coil in said chamber, a conduit for supplying refrigerant from said receiver to said coil, a conduit of substantially less cross section than said chamber connecting the bottom of the chamber and the top of the receiver, a vent from said chamber for uncondensed gases, and a valve controlling each of said conduits.

3. In a refrigerating system a receiver, a purging chamber supported above said receiver, a cooling coil in said chamber, a conduit for supplying refrigerant from said receiver to said coil, a conduit of substantially less cross section than said chamber connecting the top of said receiver and the bottom of said chamber, a vent from said chamber for uncondensed gases, a valve controlling each of said conduits and a conduit leading from the high pressure portion of the system to said chamber for conducting uncondensable gases thereto.

4. In a refrigerating system, a receiver, a purging chamber supported above said receiver, a cooling coil in said chamber, a conduit for supplying refrigerant from said receiver to said coil, a conduit of materially less cross section than said chamber leading from the bottom of the chamber into the top of the receiver, a conduit leading from the high pressure portion of said system to said chamber for conducting the uncondensable gases thereto and a vent from said chamber for the uncondensed gases.

5. In a refrigerating system, a receiver, a purging chamber supported above said receiver, a cooling coil in said chamber, a con-

duit for supplying refrigerant from said receiver to said coil, a conduit of materially less cross section than said chamber leading from the bottom of said chamber into the top of said receiver, a vent from said chamber for uncondensed gases, and means for visibly indicating the character of the discharge through said vent.

6. In a refrigerating system, a receiver, a purging chamber supported above said receiver, a cooling coil in said chamber, means to divert a portion of the refrigerant in liquid form in said system through said cooling coil, a conduit of materially less cross section than said chamber connecting the bottom of the chamber and the top of the receiver, and a vent from said chamber for uncondensed gases.

7. In a refrigerating system, a receiver, a purging chamber supported above said receiver, a cooling coil in said chamber, means to divert a portion of the refrigerant in liquid form in said system through said cooling coil, a conduit of materially less cross section than said chamber connecting the bottom of the chamber and the top of the receiver, a conduit leading from the high pressure portion of said system to said chamber for conducting the uncondensable gases thereto, and a vent from said chamber for uncondensed gases.

8. In a refrigerating system, a receiver, a purging chamber supported above said receiver, a cooling coil in said chamber, means to divert a portion of the refrigerant in liquid form in said system through said cooling coil, a conduit of materially less cross section than said chamber connecting the bottom of the chamber and the top of the receiver, a conduit leading from the high pressure portion of said system to said chamber for conducting the uncondensable gases thereto, a vent from said chamber for uncondensed gases, and means for visibly indicating the character of the discharge through said vent.

9. In a refrigerating system, a receiver, a purging chamber supported above such receiver, the top of said receiver and the bottom of said purging chamber being in communication through a passageway of materially less cross section than said purging chamber, a cooling coil in said chamber, means for supplying refrigerant to said cooling coil, and a vent from said chamber for uncondensed gases.

10. In a refrigerating system, a receiver, a purging chamber supported above said receiver, a cooling coil in said chamber, means for supplying refrigerant to said cooling coil, a conduit of materially less cross section than said chamber connecting the bottom of said chamber and the top of said receiver, means for conducting uncondensable gases from the

high pressure portion of said system to said chamber, and a vent from said chamber for uncondensed gases.

11. In a refrigerating system a receiver, a purging chamber supported above such receiver, the top of said receiver and the bottom of said purging chamber being in communication through a passageway of materially less cross section than said purging

chamber, a cooling coil in said chamber, means for supplying refrigerant to said cooling coil, a series of baffle plates within said purging chamber and a vent from said chamber for uncondensable gases.

In testimony whereof, I have signed my name to this specification.

WILLIAM W. CONNER.
